UNITED STATES PATENT OFFICE.

GEORGE HENRY CAUGHREAN, OF RAYMORE, ASSIGNOR OF TWO-THIRDS TO
JAMES W. DUCKWORTH AND LEWIS P. SUMMERS, BOTH OF HARRISON-
VILLE, MISSOURI.

DEVICE FOR CONVERTING MOTION.

SPECIFICATION forming part of Letters Patent No. 309,692, dated December 23, 1884.

Application filed June 18, 1884. (No model.)

To all whom it may concern:

Be it known that I, GEORGE H. CAUGHREAN, of Raymore, Cass county, Missouri, have invented a new and Improved Device for Con- 5 verting Motion, of which the following is a full, clear, and exact description.

The object of my invention is to provide a new and improved device for converting reciprocating motion into rotary motion.

10 The invention consists in the combination, with a shaft, of two clutch-disks mounted rigidly on the same, and two clutch-pulleys held loosely on the shaft between the fixed disks, on which clutch-pulleys cables or ropes are 15 wound in reverse directions, and which ropes have their ends secured in the end pieces of a sliding frame, whereby when the frame is reciprocated the shaft is revolved from the clutch-pulleys, which act on the clutch-disks on the 20 shaft.

Reference is to be had to the accompanying drawings, forming part of this specification, in which similar letters of reference indicate corresponding parts in both figures.

25 Figure 1 is a side view of my improved device for converting motion, parts being in section; and Fig. 2 is a sectional plan view of the same.

A shaft, A, is journaled in two bearings, B, 30 on a base, C, and on this shaft are mounted two ratchet-disks, D D', having the teeth formed on the sides facing each other, and the said disks being arranged a short distance from each other.

35 Between the disks D D' two pulleys, E E', are loosely mounted on the shaft A, which pulleys are provided with necks F F', having ratchet-teeth formed on the ends, the ratchet-teeth on the necks F F' being inclined reversely to 40 those on the adjacent disks D D'. A frame, K, is provided with longitudinal grooves in the outer surface of the top and bottom pieces, into which grooves guide-strips I pass, which are secured on the base C and on the under 45 side of a plate, G, projecting over the sliding frame K from an upright on the base. The

frame K is thus guided to reciprocate. To the tops and bottoms of the end pieces of the frame K cables or ropes H H' are secured, which are coiled once around the pulleys E E' in inverse directions, and run in grooves in the rims of the pulleys. When the frame K moves in the direction of the arrow a', the cable H' revolves the pulley E' in the direction of the arrow b', and as the neck F' of the pulley E' engages with the clutch-disk D' the said clutch-disk and the shaft A will be revolved in the direction of the arrow b'. When the frame K moves in the inverse direction of the arrow a', the pulley E is revolved in the 55 direction of the arrow b', and by means of the necks F and the disk D revolves the shaft A in the direction of the arrow b'. The reciprocating movement of the frame K is thus converted into a rotary movement of the shaft A. 60

In place of the clutcheshown and described, any other suitable clutching device can be used.

Having thus described my invention, I claim as new and desire to secure by Letters Patent— 7c

1. In a device for converting motion, the combination, with the shaft A, of the clutch-disks D D', mounted rigidly on the same, the pulleys E E', having clutch-necks F F', and mounted loosely on the shaft A between the 75 disks D D', the sliding frame K, and the cables H H', secured on the sliding frame, and wound reversely around the pulleys E E', substantially as herein shown and described.

2. In a device for converting motion, the 80 combination, with a shaft on which clutch-disks are rigidly mounted, of clutch-pulleys mounted loosely on the shaft between the clutch-disks, a reciprocating frame sliding on suitable guides, and of ropes or cables secured 85 in the ends of the frame and passed over the loose clutch-pulleys in reverse directions, substantially as herein shown and described.

GEO. HENRY CAUGHREAN.
